Joseph C. Graziano, 4315 N. Mulligan Ave., Chicago, Ill.
Filed Aug. 28, 1961, Ser. No. 66,508

Term of patent 14 years

(Cl. D80—11)

FIG. 1 is a perspective view of a display case showing my new design;

FIG. 2 is a top plan view thereof;

FIG. 3 is an end elevation view thereof;

FIG. 4 is a front perspective view of a modified form of the display case shown in FIG. 1, the rear thereof being substantially plain and unornamented; and

FIG. 5 is an end elevational view of the display case of FIG. 4.

I claim:

The ornamental design for a display case or similar article, substantially as shown and described.
